IDENTIFICATION KIT FOR BODY FLUID ANALYSIS

Edward B. Walton, Marina Del Rey, Calif. 90291

Filed Sept. 7, 1973, Ser. No. 395,224

Term of patent 14 years

Int. Cl. D24—02; D9—04
U.S. Cl. D32—1 R

FIG. 1.

FIG. 2.

FIG. 4.

FIG. 3.

FIG. 6.

FIG. 5.

FIG. 1 is a top plan view of an identification kit for body fluid analysis showing my new design.

FIG. 2 is a side elevational view as seen from the right side of FIG. 1.

FIG. 3 is a side elevational view as seen from the top of FIG. 1.

FIG. 4 is a side elevational view as seen from the bottom of FIG. 1.

FIG. 5 is a side elevational view as seen from the left side of FIG. 1.

FIG. 6 is a bottom plan view.

I claim:

The ornamental design of an identification kit for body fluid analysis, as shown.
